UNITED STATES PATENT OFFICE.

JOSEPH LÉON GOBEILLE, OF CLEVELAND, OHIO, ASSIGNOR TO THE READING STOVE WORKS, ORR, PAINTER & CO., OF READING, PENNSYLVANIA.

DESIGN FOR A HEATER.

SPECIFICATION forming part of Design No. 30,907, dated May 30, 1899.

Application filed April 6, 1899. Serial No. 712,027. Term of patent 7 years.

To all whom it may concern:

Be it known that I, JOSEPH LÉON GOBEILLE, a citizen of the United States of America, and a resident of Cleveland, in the county of Cuyahoga and State of Ohio, have invented a certain new and original Design for a Heater, of which the following is a specification, reference being had to the accompanying drawing, forming part thereof.

10 The drawing is a perspective view of a heater, showing my new design.

As shown in the drawing, the leading features of my design relate particularly to the front of the heater; and it consists in the novel form and ornamentation of the several parts thereof, as follows: The base *a*, which forms the ash-pit of the heater, is of rectangular shape, and its sides are provided with vertical ribs *b*, corresponding with the vertical lines *c* of the sectional heater-body above it. The rectangularly-shaped ash-pit front *d* has a central rise *e* from its top edge, on which is mounted a clinker-door *f*, and is provided with a rectangular bulging cleaning-door *g*, which carries a smaller rectangular draft-door *h*. A beaded edge *i* borders the ash-pit front all around, and its surface, together with the surface of the doors hung upon it, is ornamented with scrollwork *j*, as shown. The 25 main front *k* of the heater, extending upward from the ash-pit front *d*, joins the latter on each side with an outward curve *l*, then rises past the fire-pot portion of the heater with a

gradual outward curve, blending into the widened rectangular upper or combustion-chamber portion *m* of the front, the top edge *n* of which is ornamenteally curved and rounded, as shown. The central fire-door *o* is framed by a bead *p* on the front and is of bulging form, with an ornamental handle *r* and a hemispherical centerpiece *q*, provided with a diametral name or number plate *s*. Directly over the fire-door is a pair of rectangular doors *t t*, hinged near the side edges of the widened front *m* and framed by a bead *p'* on said front. The surface of these doors is ornamented, as shown, with scrollwork *u*, adjacent to the edges thereof, but leaving a plain central portion *v*, adapted for use as name-plates. An ornamental name-plate *w* is also provided, as shown, on the front *k* directly above the doors *t t*, and the surface of the front is ornamented with scrollwork *x y*, extending along the sides and top adjacent to the edges and inward a greater or less distance therefrom, as indicated.

What I claim is—

The design for a heater substantially as shown and described.

Signed by me, at Cleveland, Ohio, this 30th day of March, 1899.

JOS. LÉON GOBEILLE.
